UNITED STATES PATENT OFFICE

ARMANDO ALVARES PENTEADO, OF PARIS, FRANCE

STRETCHING DEVICE, PARTICULARLY APPLICABLE TO THIN PHONOGRAPHIC DISKS

Original application filed July 8, 1929, Serial No. 376,698, and in France June 12, 1929. Divided and this application filed August 18, 1930. Serial No. 476,223.

The present invention relates to a stretching device which allows thin disks, and more particularly those which form the subject of specification Ser. No. 376,698 filed July 8, 1929, of which this is a division, to be rigidly held in place, and also to be readily cut. This apparatus comprises essentially two concentric disks formed in the manner of an embroidery frame. The outer disk comprises a gripping device such as a screw which passes through lugs which form part of the disk, and the inner disk has on its upper surface a groove in which a cutting member engages in order to effect cutting the disk after recording has been effected.

One form of construction of the invention is illustrated in the annexed drawing, in which:—

Fig. 1 is a plan view, partly in section, of the disk stretching device.

Fig. 2 is a section on the line 2—2 of Fig. 1.

Figs. 3 and 4 are sectional side views on the line 3—3 of Fig. 1, showing the manner in which the disk is placed on the stretching device.

Fig. 5 is a sectional view on a larger scale, showing how cutting of the disk is effected, and

Fig. 6 shows the manner of using a disk on which recording is being effected.

The disk *a*, which is preferably of viscose or the material known under the registered trade-mark as "Cellophane" as described in specification No. 376,698 filed July 8, 1929, is subjected to preliminary softening to facilitate recording, preferably by soaking in water.

As shown in Fig. 3, the disk *a* is placed on a ring *b*, which it overlaps throughout the whole of its periphery; to the upper part of the disk is applied a second ring *c* which is of slightly larger diameter than the ring *b*, and this is cut away at *d* in order that it may be gripped on the periphery of the ring *b*

by means of a screw *e* which engages lugs *c'*, *c''* of the ring *c*.

When the latter is forced on to the ring *b* the disk *a* is perfectly stretched, as shown in Fig. 4, owing to the fact that the overlapping edge of the disk is bent down by means of the ring *c*.

The screw *e* is then tightened to hold the disk in its stretched position, and a hole is pierced in the centre of the disk, recording being finally effected on both surfaces.

After the recording has been effected, and after the disk has been thoroughly dried it is cut by means of a cutting member *f* which is passed through the sheet into a small circular groove *b'* formed on the upper surface of the ring *b*, and which is caused to follow the said circular groove.

The disk *a'* thus formed, and which has been subjected to recording on one or both of its surfaces, may be utilized in gramophones having a light tone arm and a diaphragm.

In particular, there can be employed either for recording on a disk or for the reproduction of sounds from a disk a phonographic apparatus of the type forming the subject of French Patent No. 573,131 in the name of the present applicant, dated 14th November, 1923.

The disk *a'* is held in place on the turn-table *i* of the gramophone by means, for example, of a ring *h* which is placed above the disk on the said turn-table *i*.

It is obvious that modifications may be introduced into the process and apparatus described above without departing from the spirit of the invention. For example, the application of the stretching device is not limited to disks having a cellulose base, but may be utilized in connection with thin sheets of any composition or material in connection with direct phonographic recording.

What I claim is:—

Stretching device for thin phonographic

disks comprising a ring for receiving the
softened disk provided with a circumferential
groove in one of its plane annular faces
and a ring of slightly larger diameter adapt-
ed to be forced on the other ring so as to
engage the overlapping edge of the disk,
whereby the disk is stretched and the record-
ing effected thereon, the disk then dried, and
cut by any cutting member inserted in the cir-
cumferential groove.

10 In testimony whereof I have signed this
specification.

ARMANDO ALVARES PENTEADO.
